(57) **CLAIM**

The ornamental design for a cycling helmet, as shown and described.

DESCRIPTION

FIG. 1 is a top front perspective of a cycling helmet showing our new design;

FIG. 2 is a bottom rear perspective view thereof;

FIG. 3 is a front view thereof;

FIG. 4 is a rear view thereof;

FIG. 5 is a side view thereof;

FIG. 6 is a second side view thereof;

FIG. 7 is a top view thereof; and,

FIG. 8 is a bottom view thereof.

The shade lines in the Figures show contour and not surface ornamentation.

1 Claim, 8 Drawing Sheets
